UNITED STATES PATENT OFFICE

ADOLPH RUBIN, OF LEIPZIG, GERMANY, ASSIGNOR TO THE FIRM ADOLF BLEICHERT & CO. A.-G. OF LEIPZIG, GERMANY

PROCESS FOR THE WORKING OF PASSENGER ROPEWAYS WITH CONTINUOUS TRAFFIC

Application filed November 8, 1930, Serial No. 492,981, and in Germany March 14, 1930.

This invention relates to the operation of suspended or otherwise supported vehicles, such as tram cars, by means of travelling ropes or cables, and has among its objects to 5 provide novel means for bringing a car from a state of rest gradually up to the rate of speed of the main power rope or cable in instances where the main power rope moves constantly at a fixed or substantially fixed 10 rate of speed; to provide for either automatic or manual coupling of the car to the main power rope when the car has attained either the speed of the main power rope or any other suitable or desired speed; to provide for 15 either automatic or manual disconnection of the car from the means for initiating movement thereof, and to provide means of a simple, reliable and thoroughly practicable nature to accomplish such purposes.

20 With the foregoing and other objects in view, which will become more apparent as the nature of the invention is better understood, the same consists in the novel combination and arrangement of features as will 25 be hereinafter more fully described, illustrated in the accompanying drawings and defined in the appended claims.

In the drawings, wherein like characters of reference denote corresponding parts in the 30 respective views:

Figure 1 is a view partly in elevation and partly in transverse section illustrating the car equipment in accordance with a practical embodiment of the invention; and

35 Figure 2 is a diagrammatic side elevation illustrating different operative positions of the car.

According to the particular embodiment of 40 the invention illustrated in the drawings, the car, designated generally as 10, is equipped with a trolley 11 and by means of said trolley is suspended from a rail 12 for travel therealong.

45 Power for moving the car 10 along the rail 12 is furnished by a main power rope or cable designated as *a*, and a secondary power rope or cable designated as *b*, these ropes or cables extending in side to side spaced relation be- 50 low the rail 12 and being driven in any suit-

able or desired manner not entering into the invention.

The main power rope *a* travels constantly at a fixed or substantially fixed rate of speed, but the rate of travel of the secondary power 55 rope *b* is variable between minimum and maximum speeds, the maximum speed thereof preferably being equal or substantially equal to the normal speed of travel of the main power rope *a*, and the minimum speed thereof being either zero or any relatively low 60 speed desired. In other words, while the rope *a* travels at a given rate of speed, the rope *b* starting from a state of rest or from its lowest speed, gradually increases in speed 65 to the speed of the rope *a*, slows down or stops as the case may be, again gradually increases in speed to the speed of the rope *a* and continues this variable speed operation. Thus, when the car 10 is in a state of rest, it 70 may, by being coupled to the cable *b* when the latter is in a state of rest or is travelling at a relatively low rate of speed, be brought by said cable gradually up to the speed of travel of the cable *a* and then be coupled to the 75 latter cable, whereby all shocks such as would occur by a coupling of the car initially with the cable *a* may be avoided.

The means for coupling the car with and uncoupling the same from the ropes *a* and *b* 80 is illustrated in the present instance as comprising a pair of clamp devices carried by the car for cooperation with the ropes *a* and *b*, respectively, and each inclusive of a fixed jaw and a movable jaw, the fixed jaws being 85 constituted by the opposite side portions of an upward extension *c'* of a bracket *c* suitably mounted on the car, and the movable jaws, designated as *g* and *f*, respectively, being constituted by members pivoted to the 90 bracket *c* at opposite sides thereof for swinging movement towards and from their related side portions of the upward extension *c'*.

The ropes *a* and *b* are disposed, respectively, between the jaws *g* and *f* and the adjacent 95 sides of the fixed jaw elements *c'* so that by inward swinging movement of either of the movable jaws the car is coupled to the related rope, and by outward swinging movement of the jaws the car is uncoupled from 100

the ropes for continued travel of the ropes without effect to move the car. Coil springs interposed between the element c' and the jaws g and f , or other means of an equivalent nature, preferably are provided to urge the jaws to their outwardly swung or released positions.

Extending through the element c' and the jaws g and f and projecting beyond the outer faces of said jaws is a shaft l the end portions of which are screw threaded and ~~are~~ threaded thereon the hub portions o and p , respectively, of a pair of levers i and k . The inner ends of said hub portions are disposed in engagement with the outer faces of the jaws g and f , respectively, and the shaft l is fixed to the element c' , and thus, by swinging movement of either lever in one direction or the other its hub is moved either inward or outward as the case may be to move the related clamp jaw either inward or to release it for outward movement to effect either coupling or uncoupling of the related power cable with or from the car.

25 The levers i and k are adapted for automatic actuation by means of cam devices suitably arranged along the rail 12, whereby coupling and uncoupling of the car with and from the power ropes a and b is effected in a predetermined manner. However, it is desirable that coupling and uncoupling of the car with and from the power ropes be placed also under the manual control of the operator of the car, and to this end the hub portions of the levers i and k have fixed thereto sprocket wheels m and n , respectively, over which are trained sprocket chains q and r , respectively, which extend into the car over sprocket wheels t equipped with suitable means for manually rotating the same. Thus, rotation of the hubs o and p to couple the car with or uncouple the same from either cable a or b may be effected manually as well as automatically.

45 In Figure 2 of the drawings is illustrated a cam device e' for actuating the lever k to effect coupling of the car to the rope b ; a cam device e^2 spaced a suitable distance along the rail 12 from the cam device e' for actuating the lever i to effect coupling of the car to the rope a , and a cam device e^3 suitably arranged with respect to the cam device e^2 for actuating the lever k to effect release of the car from the cable b .

55 Assuming the car to be in a state of rest adjacent to the cam device e' , sufficient movement of the car is effected in any desired manner to cause the lever k to engage and be swung by the cam device e' to cause the rope b to be clamped between the element c' and the jaw f , or, alternatively, the cam device e' may be eliminated and the chain r may be manipulated to accomplish the same purpose. In either event, coupling of the car with the rope b is effected while the rope

is in a state of rest or is moving slowly, and thus, as the speed of travel of said rope is accelerated, the car is brought up to the speed of travel of the rope a . At or about this time the lever i strikes the cam device e^2 70 and is swung thereby to effect coupling of the car to the cable a , and immediately thereafter, or at any other proper time, the lever k , by continued movement of the car, strikes the cam device e^3 and is swung thereby to uncouple the car from the rope b . The car now being carried along by the cable a continues to travel therewith until a cam device similar to those shown is struck by the lever i , whereupon said lever is swung to 80 uncouple the car from the cable a , or, alternatively, uncoupling of the car from the cable a may be manually effected at any time desired by manipulation of the chain q .

The levers i and k preferably are equipped with rollers d for cooperation with the cam devices, and guide sheaves h preferably are provided adjacent to the clamp jaws f and g to support the ropes a and b when the latter are moving idly through the open clamp devices.

While only a single embodiment of the invention has been illustrated and described, it is obvious that the features of the invention may be embodied in various other mechanical structures within the spirit and scope of the invention as defined in the appended claims.

I claim:

1. A track, a vehicle movable therealong, a pair of power ropes extending contiguous to the track and travelling, respectively, one at a substantially constant rate of speed and the other at a variable speed, and means for coupling and uncoupling the car selectively with and from said ropes.

2. A track, a vehicle movable therealong, a pair of power ropes extending contiguous to the track and travelling, respectively, one at a substantially constant rate of speed and the other at a variable speed, and means operable in response to movement of the car along the track to couple and uncouple the car with and from said cables in a predetermined manner.

3. A track, a vehicle movable therealong, a pair of power ropes extending contiguous to the track and travelling, respectively, one at a substantially constant rate of speed and the other at a variable speed, and a pair of rope clamp devices carried by the car for cooperation with said ropes, respectively, and separately operable to couple and uncouple the car with and from the respective ropes.

4. A track, a vehicle movable therealong, a pair of power ropes extending contiguous to the track and travelling, respectively, one at a substantially constant rate of speed and the other at a variable speed, a pair of rope clamp devices carried by the car for cooperation with said ropes, respectively, and actu-

ating devices located along the track for co-operation with said clamp devices to actuate the latter to couple and uncouple the car with and from the respective ropes in predetermined sequence.

5. A track, a vehicle movable therealong, a pair of power ropes extending contiguous to the track and travelling, respectively, one at a substantially constant rate of speed and 10 the other at a variable speed, means for coupling the car to the second mentioned rope, means operable by movement of the car with said second mentioned rope to couple the car to the first mentioned rope, and means operable by continued movement of the car to uncouple the same from the second mentioned rope.

6. A track, a vehicle movable therealong, a pair of power ropes extending contiguous 20 to the track and travelling, respectively, one at a substantially constant rate of speed and the other at a variable speed, a pair of clamp devices carried by the car for cooperation with said ropes, respectively, to couple and 25 uncouple the car with and from said ropes, means for manually actuating each clamp device to effect coupling and uncoupling of the car with and from said ropes, and means operable in response to movement of the car to 30 effect coupling and uncoupling of the same with and from said ropes automatically in predetermined sequence.

7. A track, a vehicle movable therealong, a pair of power ropes extending contiguous 35 to said track and travelling, respectively, one at a substantially constant rate of speed and the other at a variable speed, a pair of clamp devices carried by the car for cooperation with said ropes to couple and uncouple the 40 car with and from said ropes, each clamp device including a fixed jaw and a movable jaw, a fixed threaded shaft, a member threaded on the shaft and adapted by threaded movement therealong for cooperation with the 45 movable jaw to move the same toward the fixed jaw, means for manually rotating said member, and a lever arm carried by said member for cooperation with an element located along the track to effect automatic rotation 50 of said member either to move the movable jaw in a rope clamping direction or to permit the same to move in a rope releasing direction.

55 In testimony whereof I affix my signature.
ADOLF RUBIN.
